UNITED STATES PATENT OFFICE.

SEBASTIANO PIOMBO, OF SAN FRANCISCO, CALIFORNIA.

SACKING STAND.

Application filed March 3, 1924, Serial No. 696,575. Renewed September 22, 1928.

This invention relates to an improved sacking device for holding sacks, bags and like flexible receptacles in position to have coal, grain, mail, etc., dumped therein, in an expeditious manner without spilling or waste of the material being sacked.

An object of the invention is to provide a sack filling stand of the character described which is inexpensive, compact and capable of being easily handled and operated.

Another object is to provide a device of the character described which is readily and easily adjustable to provide for filling sacks or bags of different sizes.

Another object of the invention is to provide a portable sacking stand such as above described, which may be easily moved as desired and which will not tear or rip the sacks.

Another object is to provide a novel means for automatically locking the bag holding means against accidental release of the bag.

A further object is to provide in a device of the character described a novel means for automatically closing bags or sacks of the type which have a draw cord for closing the open ends of such sack, which means operates on release of the sack or bag from the stand.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

Referring to the drawing:

Fig. 1 represents a side elevation of the device of the invention.

Fig. 2 is a similar view showing the device used as when employed with draw cord sacks or bags.

Fig. 3 represents a perspective view of the device.

Fig. 4 represents a fragmentary enlarged side elevation of a detail of construction.

The embodiment of the invention shown in the accompanying drawing comprises an open base 1, supported by several castings 2 and having a standard 3 at one end thereof. A substantially U-shaped horizontally disposed frame 4 is vertically adjustably mounted in the standard, being held in ad-

justed position by bolts 5. This frame extends over the base and supports means for releasably holding a sack or bag in the stand. The frame is adjusted to the proper height to support the open end of the bag fully opened while the bottom of the bag rests on the ground, although in certain instances, the bottom of the sack will be spaced above the base, as shown in Fig. 2.

The means for supporting and releasing the sacks comprises two shafts 6 and 7 mounted on the side pieces 8 and 9 of the frame and provided at certain ends with crank arms 10 and 11, joined by a link 12.

The shaft 6 has an operating lever 13 attached thereto, which lever, when lifted, will rotate the two shafts in opposite directions. Each of the shafts is provided with upstanding pointed pins 14 on which the sack is im-

paled in order to be supported with its upper end open. Surrounding the shaft 6 is a spring 14, which is placed under tension when the shaft is rocked and serves to return said shaft, also the shaft 7 to normal position with the pins extending in upright position.

With a bag engaged on the pins and standing in upright position as shown in Fig. 1, when it is desired to release the bag or sack, the operator pulls up on the lever and rotates the shafts so that the pins will be turned into downwardly and inwardly inclined positions and allow the sack or bag to slip off of them free of the stand. The lever is pivoted as at 15 in a slot 16 formed in the shaft 6 and is adapted to engage under a locking member or keeper 17 fastened to one side of the frame 4.

In operating the lever it is pulled outward and upward away from the keeper until the shafts have been rotated to the desired extent.

On release of the lever it pulls downwardly and inwardly so that it will engage behind the keeper and thereby automatically lock the lever against movement. Thus, if the weight of the material in the sack or bag is sufficient to cause the shafts to rotate and the pins to release the sack, the lever being locked in this manner, will prevent such action.

To provide for filling the sacks or bags of the draw cord or string type and for automatically closing the sacks or bags on release thereof, a hook 18 is pivoted as at 19 in a slot 20 formed in the upper part of the standard 3. This hook is actuated by a rod 21 pivoted to the inner end thereof. The rod 21 is pivoted to a bell crank 22 mounted at the lower end of the standard. The bell crank has a

link 23 connected thereto, which link is actuated by a pedal 24 mounted on the base 1. When the pedal is depressed, the hook is rocked on its pivot so that the draw string, 5 as shown at 25, will slip off of the hook and free the sack or bag from the stand. As shown in Fig. 2, a sack of the draw cord or string type, is mounted in the usual manner on the pins but so that the lower end of the 10 sack is spaced above the ground and base member, the draw cord being looped over the hook, as shown in said figure. After the sack is filled, the operator lifts up on the lever and rotates the shafts so that the pins 15 will release the stack. As the sack falls, the draw string pulls the open end of the sack closed and when the sack comes to rest with the open end closed, the operator depresses the pedal and releases the draw string from 20 the hook 18. In this manner, the action of filling and closing a draw string type of bag or sack may be expeditiously carried out. The stand may therefore be used to great advantage for filling and closing mail sacks 25 or bags.

The device of the invention is compact, capable of being readily moved about from place to place and simple as to construction

and operation, as well as being inexpensive. All of these features contribute to an efficient 30 sack or bag filling operation at a saving in time, labor and expense as compared to the ordinary hand methods of filling sacks or bags.

I claim:

A sacking stand comprising a standard, a frame supported by the standard and including spaced horizontal arms between which a sack is adapted to be placed, shafts rotatably mounted on the upper sides of said arms, 40 crank arms projecting from the ends of said shafts, pins projecting upwardly from said shafts, a spring associated with said frame and said shafts normally maintaining the pins extending upwardly above said shafts and providing for movement of the pins downward and inward so as to point towards one another, a link pivotally connected at its ends with the crank arms, an operating lever connected with one of said rotatable shafts, 45 said pins and rotatable members being arranged to permit a sack to be placed between the shafts and up over the pins whereby when the pins are swung downward and inward the sack will slip off the pins.

SEBASTIANO PIOMBO.
